UNITED STATES PATENT OFFICE.

ARTHUR CRANSTON, OF ATLANTIC CITY, NEW JERSEY.

SHELF AND SIMILAR STRUCTURE.

Application filed June 16, 1925. Serial No. 37,515.

My invention relates to shelves and analogous structures, and especially to "knock down" shelves which are very strong and rigid when set up and arranged for use, and which may be easily and quickly taken apart, arranged very compactly for transportation, and easily and quickly reassembled.

The characteristics, objects and advantages of the invention are sufficiently explained hereafter, in connection with the detail description of the accompanying drawings, which show one exemplifying structure embodying the invention. This particular embodiment of the invention is what I call a corner shelf, in distinction from a straight shelf disclosed in a companion application. After considering the present embodiment of the invention, skilled persons will understand that many variations may be made without departing from the invention, and I contemplate the employment of any structures that are properly within the scope of the appended claims.

Fig. 1 is a perspective view of a corner shelf structure embodying the invention in one form.

Fig. 2 is a section at 2—2, Fig. 1.

Fig. 3 is a bottom plan with one of the rear or supporting members partly removed or displaced from normal position.

Fig. 4 is a detail perspective of the shelf section connector or interlocking member.

Fig. 5 is a perspective detail of one of the rear or supporting members.

Fig. 6 is a cross-section of the same.

Fig. 7 is a bottom plan showing the manner in which the two shelf sections are put together.

Figs. 8 and 9 are perspective views from below of the two shelf sections.

Fig. 10 shows one compact arrangement of the parts "knocked down" for shipment.

This shelf is especially designed to be supported in a wall corner as shown in Fig. 1, where the walls join at a right angle as usual. The shelf structure comprises the two main or shelf sections proper, 1 and 2, an interlocking member or connector 16, and rear or supporting members 24 and 27. The parts may be made of various materials, but it is usually preferred to make them of a strong light metal, or metallic alloy, of which duralumin is one example. The parts may be produced of such alloys by die casting methods in rapid and economical fashion, and with complete or nearly complete

elimination of any machining operations. The parts may also be made of moderate cross-section and at the same time are very strong, rigid and practically indestructible. 60

The shelf sections preferably are in the form of equilateral triangles, and when placed together with the edges 6 and 7 in contact as shown in Fig. 1, they form another equilateral triangle, fitting the wall 65 corner and of any desired or reasonable depth. The adjacent edges of the shelf sections are interlocked by formations conveniently called tongue and groove formations, including a tongue 8 projecting from the 70 edge 6 of section 1 and of T-cross section to co-operate with a groove 9 of similar cross-section in the edge 7 of section 2. The tongue 8 extends from one corner of its shelf section to a point substantially distant 75 from the front shelf edge 10, and the groove 9 is similarly dimensioned. These parts are connected in the manner indicated in Fig. 8 by inserting the end 11 of tongue 8 in the rear end of the groove 9 and moving shelf 80 section 2 relative to section 1, as indicated by the arrow, Fig. 7, until the end 11 of tongue 8 encounters the end of groove 9. The front shelf edges 10 and 12 are then in line. The shelf sections are additionally connected 85 or interlocked by T-section tongues or ribs 14 on the lower shelf faces adjacent and parallel the edges 6 and 7. These ribs extend from the front shelf edges to points substantially distant from the rear corners 90 15. To co-operate with these ribs, a connector or interlocking member 16 is provided, which has parallel grooves 17 of T-section to fit the ribs 14. The rear corners of this rectangular connector are cut away 95 forming angular or beveled faces 18, later referred to. After the shelf sections have been interconnected, as above explained, the connector 16 is applied to the end shelf surfaces and moved forward from the rear, so 100 that the rear ends of the ribs 14 enter the front ends of grooves 17. The connector is stopped in the proper position with its front end in line with the front shelf edges by the engagement of the rear ends of the ribs with 105 the rear ends of channels 17.

The shelf sections 1 and 2 also have on their lower faces adjacent and parallel the edges 20, tongues 21 and 22 respectively of T-section, extending from the front edges 10 110 and 12 to points well removed from the rear corners 15. The tongue 21 co-operates with

2
a groove 23 of T-section in a rear or supporting member 24, which has a beveled front end 25 to conform to the direction of the front shelf edge, when the supporting member is in position. Tongue 22 co-operates with a similar groove 26 in a rear or supporting member 27 which is in general similar to member 24, except that it is shorter than the latter to the extent of the width of one of the members. The supporting members are applied by first positioning the member 27 below shelf section 2 and moving it parallel to edge 20 until the tongue 22 is fully engaged in groove 26. Supporting member 24 is then positioned and moved in a similar way parallel to edge 20 of shelf section 1 until tongue 21 is fully engaged in channel 23. In this movement the support 24 passes close to the rear end of support 27 and both of the supports in their described assembly movements pass close to the beveled faces 18 of connector 16.

Desirably, in some cases, the rear ends of the supports are additionally interlocked by forming a socket 30 in member 27, and a closely fitting lug 31 on member 24. The lug enters the socket when member 24 is moved to its operative position. All of the members are now interlocked and secured against inadvertent displacement, except member 24. Shelf sections 1 and 2 cannot be moved relatively in any direction because of their connection by connector 16, and also by their connection with the interlocked supporting members 24 and 27. The connector cannot be displaced forward because of the engagement of ends of the shelf ribs and the connector channels respectively, and it cannot move backward because of the engagement of its beveled faces or corners 18 with the adjacent support member. Supporting member 20 cannot be slid backward because its rear end abuts against the support 24. Support 24 is prevented from rearward displacement when the shelf is erected in a wall corner. The rear end of the supporting member 24 then engages one of the walls.

Convenient supporting means are provided, such as screw holes 35 in the supporting members through which screws may be inserted into the wall surfaces.

When the shelf is erected in a wall corner, as shown in Fig. 1, it is very firmly and rigidly supported by the two supporting members or strips which are secured to the right angled wall surfaces. The central part of the shelf where the two sections intersect, is securely held against any perceptible bending or vertical displacement by the interlocking connection of the shelf edges, and the further rigid connection and brace provided by the connector 16. The parts are furthermore prevented from any accidental displacement by their mutual engagement or

interlocking action, and the engagement of the rear end of supporting member 24 with a wall surface, as above described.

An important feature of the invention is the arrangement of the parts so that they are all connected by movement of the successive parts from the rear toward the front of the structure. This assembly method or arrangement has been described above in detail. The parts are easily disconnected for packing and shipment by substantially reverse operations, that is, support 24 is first moved downward or rearward to the right, as viewed in Fig. 3; support 27 is then moved downward or rearward and to the left and connector 16 is then moved to the rear, and the shelf sections 1 and 2 are then disconnected by moving one downward or to the rear in relation to the other. The disconnected parts may be arranged in various compact ways for shipment in small space. Fig. 10 shows one preferred arrangement in which the longer edges of two shelf sections are placed together, producing a square arrangement whose greatest dimension is only one-half the greatest dimension of the erected shelf. The supports 24 and 27 are then laid along two sides of a square, and the connector 16 is placed on top of one of the shelf sections between its ribs.

There is thus provided at low cost a very simple, light and practically indestructible shelf structure, which may be quickly and easily set up for use or taken down for transportation in compact form. This does away with a common annoyance and expense incident to present day housing conditions, namely, the common practice of erecting more or less permanent wooden shelving which is usually left in place when the premises are vacated, and therefore represents a total loss to the tenant.

I claim:

1. A corner shelf structure comprising two substantially triangular shelf sections, provided with slidably engaged interlocking tongue and groove formations at adjacent sides whereby the sections may be detachably connected to form a composite triangular shelf, and a connector having parallel grooves to co-operate with slidably interlocking tongues on adjacent face portions of the shelf sections.

2. A corner shelf structure comprising two substantially triangular shelf sections, provided with slidably engaged interlocking tongue and groove formations at adjacent sides whereby the sections may be detachably connected to form a composite triangular shelf, and supporting members having groove formations slidably engaged with interlocking tongue formations adjacent diagonally disposed edges of the respective shelf sections.

3. A corner shelf structure comprising two substantially triangular shelf sections, provided with slidably engaged interlocking tongue and groove formations at adjacent sides whereby the sections may be detachably connected to form a composite triangular shelf, and supporting members having groove formations slidably engaged with interlocking tongue formations adjacent diagonally disposed edges of the respective shelf sections, one of the supporting members having a portion overlapping the rear end of the other.

4. A corner shelf structure comprising two substantially triangular shelf sections, provided with slidably engaged interlocking tongue and groove formations at adjacent sides whereby the sections may be detachably connected to form a composite triangular shelf, and supporting members having groove formations slidably engaged with interlocking tongue formations adjacent diagonally disposed edges of the respective shelf sections, the parts being readily disconnectible by rearward sliding movement of respective parts and being dimensioned for packing in a space whose greatest dimension is substantially no greater than one-half the greatest linear dimension of the composite shelf when set up for use.

5. A corner shelf structure comprising two substantially triangular shelf sections, provided with slidably engaged interlocking tongue and groove formations at adjacent sides whereby the sections may be detachably connected to form a composite triangular shelf, and a connector having parallel grooves to co-operate with slidably engaged interlocking tongues on adjacent face portions of the shelf sections.

6. A corner shelf structure comprising two substantially triangular shelf sections, provided with slidably engaged interlocking tongue and groove formations at adjacent sides whereby the sections may be detachably connected to form a composite triangular shelf, a connector having parallel grooves to co-operate with slidably engaged interlocking tongues on adjacent face portions of the shelf sections, and supporting members having groove formations slidably engageable with interlocking tongue formations adjacent diagonally disposed edges of the respective shelf sections.

7. A corner shelf structure comprising two substantially triangular shelf sections, provided with slidably engaged interlocking tongue and groove formations at adjacent sides whereby the sections may be detachably connected to form a composite triangular shelf, a connector having parallel grooves to co-operate with slidably engaged interlocking tongues on adjacent face portions of the shelf sections, and supporting

members having groove formations slidably engageable with interlocking tongue formations adjacent diagonally disposed edges of the respective shelf sections, one of the supporting members having a portion overlapping the rear end of the other.

8. A corner shelf structure comprising two substantially triangular shelf sections, provided with slidably engaged interlocking tongue and groove formations at adjacent sides whereby the sections may be detachably connected to form a composite triangular shelf, a connector having parallel grooves to co-operate with slidably engaged interlocking tongues on adjacent face portions of the shelf sections, and supporting members having groove formations slidably engageable with interlocking tongue formations adjacent diagonally disposed edges of the respective shelf sections, the supporting members engaging rear portions of the connector and preventing rearward displacement thereof.

9. A corner shelf structure comprising two substantially triangular shelf sections, provided with slidably engaged interlocking tongue and groove formations at adjacent sides whereby the sections may be detachably connected to form a composite triangular shelf, a connector having parallel grooves to co-operate with slidably engaged interlocking tongues on adjacent face portions of the shelf sections, and supporting members having groove formations slidably engageable with interlocking tongue formations adjacent diagonally disposed edges of the respective shelf sections, the supporting members engaging rear portions of the connector and preventing rearward displacement thereof, the parts being readily disconnectible by rearward sliding movement of respective parts and being dimensioned for packing in a space whose greatest dimension is substantially no greater than one-half the greatest linear dimension of the composite shelf when set up for use.

10. A knock-down corner shelf structure adapted for removable mounting in a wall-corner or similar location, comprising two substantially triangular shelf sections having straight abutting edges, the two sections when said edges abut providing a composite triangular shelf, and a connector adapted to lie against the lower faces of the sections and to overlap the joint at said abutting edges, the sections and connector being provided with slidably engaged interlocking formations by which the connector detachably secures the sections together in stated relation.

Signed at Atlantic City, N. J. in the county of Atlantic and State of New Jersey, this 12th day of June, A. D. 1925.

ARTHUR CRANSTON.
